(57) **CLAIM**

We claim the ornamental design for a work area screen, as shown and described.

DESCRIPTION

FIG. 1 is a top front-right perspective view of a first embodiment of a work area screen;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and

FIG. 8 is a bottom front-right perspective view thereof;

FIG. 9 is a top front-right perspective view of a second embodiment of a work area screen;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a bottom front-right perspective view thereof; and,

FIG. 17 is a top front-right perspective view of the first embodiment shown in an environment of use.

The broken lines in FIGS. 9-10, 15, and 16 illustrate portions of the article that form no part of the claimed design. The broken lines in FIG. 17 illustrates environment that forms no part of the claimed design.
